UNITED STATES PATENT OFFICE.

ALBERT C. ARMBRUSTER, OF LOS ANGELES, CALIFORNIA.

DESIGN FOR A ROPE-BRAKE FOR FIRE-ESCAPES.

SPECIFICATION forming part of Design No. 32,172, dated January 30, 1900.

Application filed October 24, 1899. Serial No. 734,690. Term of patent 7 years.

To all whom it may concern:

Be it known that I, ALBERT C. ARMBRUSTER, a citizen of the United States, residing at Los Angeles, in the county of Los Angeles and State of California, have invented and introduced a new and original Design for a Rope-Brake for Fire-Escapes, of which the following is a specification, reference being had to the accompanying drawing, forming a part thereof.

The drawing shows a perspective view of the rope-brake for fire-escapes constructed in accordance with my invention.

As shown in the drawing, the leading feature of my design consists of a main shaft *a*, which is circular in cross-section and which is provided with disks *b* and *c*, one at each end and placed at right angles to the shaft *a* at opposite sides thereof. The disks *b* and *c* are provided with perforations *e* and *f*. Rectangular members *g* and *h* are also formed

upon the ends of the shaft *a*, which said rectangular members are slotted longitudinally and horizontally, as shown at *i* and *k*. The peripheries of the disks *b* and *c* are rounded, 25 as also are the walls of the members *g* and *h*. As these members are of a slightly-greater thickness than that of the disks, the upper wall of the upper member and the lower wall of the lower member are not in the same plane 30 with the corresponding faces of the disks.

Having thus described my invention, what I claim as new, and desire to secure by Letters Patent, is—

The design for a rope-brake for fire-escapes 35 as herein shown and described.

In testimony whereof I affix my signature in the presence of two witnesses.

ALBERT C. ARMBRUSTER.
